Primary Examiner—Philip S. Hyder**[57] CLAIM**

The ornamental design for an arrowhead sharpener and wrench combination, as shown and described.

DESCRIPTION

FIG. 1 is a right side elevational view of an arrowhead sharpener and wrench combination embodying my design, the left side being a mirror image thereof;

FIG. 2 shows a top plan view of the design as shown in FIG. 1, the bottom plan view being identical thereto; and, FIG. 3 shows a rear end view of the design as shown in FIG. 1, the front end view being identical thereto.
